DESIGN.

J. BEESLEY.

Heating-Stoves.

No. 6,697.

Patented June 3, 1873.

UNITED STATES PATENT OFFICE.

JACOB BEESLEY, OF PHILADELPHIA, PENNSYLVANIA, ASSIGNOR TO
SAMUEL SMITH, OF SAME PLACE.

DESIGN FOR A HEATING-STOVE.

Specification forming part of Design No. **6,697**, dated June 3, 1873; application filed May 24, 1873.

To all whom it may concern:

Be it known that I, JACOB BEESLEY, of the city of Philadelphia, in the State of Pennsylvania, have invented a Design for Stoves, of which the following is a specification:

The nature of my design is fully represented in the accompanying engraved illustration, to which reference is made.

A represent a cylindrical stove, having an ornamented cap or top plate, **C**, fuel-door **D**, and its supporting-frame **d'**, base **E**, and legs **F**, to the contour and ornaments of which parts my design is confined.

My design consists, first, of the contour and the bas-relief ornamental figures 1 1 of the cap or top plate **C**; second, of the contour and the edge molding 2 of the frame **d'** of the fuel-door **D**; third, of the contour of the fuel-

door **D**, the raised edge molding 3 thereof, and the bas-relief ornamental figures 4 and 5 on the flat panel of said door; fourth, of the bas-relief ornamental figures 6 6 on the top plate **e'** of the base **E**; fifth, of the bas-relief ornamental figures 7 7 on the body-plate **e''** of the base **E**; sixth, of the contour of the bottom-plate **e'''** and the ornamented molding 8 of the same; and, seventh, of the contour and the bas-relief ornamental figures 9 and 10 of the legs **F**.

What I claim as my invention is—

The design for a stove, substantially as described and shown.

JACOB BEESLEY.
